UNITED STATES PATENT OFFICE.

AUGUST VICTOR LARSON, OF BROOKLYN, NEW YORK.

EXPANSION-ENGINE.

1,343,056.

Specification of Letters Patent. Patented June 8, 1920.

Application filed June 8, 1918. Serial No. 238,933.

To all whom it may concern:

Be it known that I, AUGUST VICTOR LARSON, a citizen of the United States, residing at Brooklyn, in the county of Kings and 5 State of New York, have invented certain new and useful Improvements in Expansion-Engines; and I do hereby declare the following to be a full, clear, and exact description of the invention, such as will enable others skilled in the art to which it 10 pertains to make and use the same.

The object of the invention is to provide a simple and economical expansion engine of the caloric type, wherein air or similar fluid 15 agent serves as the expansion medium, and which, introduced at a low temperature and applied to the piston or other power element of the mechanism at a high temperature, relatively to that of introduction, serves to 20 actuate an efficient driving unit, and with this general object in view, the invention consists in a construction, combination and relation of parts hereinafter specifically explained, it being understood however that 25 changes in form proportion and details may be resorted to, within the scope of the appended claims without departing from the spirit of the invention.

In the drawings:

30 Figure 1 is a side view of an engine representing a preferred embodiment,

Fig. 2 is a plan view of the same,

Fig. 3 is a vertical central sectional view,

Fig. 4 is a horizontal sectional view, taken 35 on the plane indicated by the line 4—4 of Fig. 3,

Fig. 5 is a similar sectional view on the plane 5—5 of Fig. 3,

Fig. 6 is a similar sectional view on the 40 plane 6—6 of Fig. 3,

Fig. 7 is another transverse sectional view on the plane 7—7 of Fig. 3,

Fig. 8 is a side view of a tubular core unit serving to define the compartments of the 45 compression chamber,

Fig. 9 is a plan view of the core shown in Fig. 8,

Fig. 10 is a side view of the operating valve, and

50 Fig. 11 is a detail view in perspective of the motion transmitting element by which the motion of the valve is controlled.

Essentially the engine embodies a heating element represented illustratively by the 55 steam jacket 20, suitably supported upon a base 21 and having inlet 22 and outlet 23, a

compression chamber 24, bounded exteriorly by the cylindrical wall 25, which also forms the inner wall of the steam jacket, and bounded interiorly by a tubular unit 26, represented in detail in Figs. 8 and 9, a piston cylinder 27 formed by the bore of the tubular unit 26 and having a reciprocatory piston 28 mounted therein, and an operating valve 29 for controlling the inlet and exhaust of the expansion medium and also for controlling certain compression and expansion ports constituting the means of access to and egress from the compression chamber, as hereinafter more fully explained, 60 with reference to the piston cylinder and the action of the piston therein. The outer shell constituting the exterior wall of the steam jacket, as shown at 21, may be flanged inwardly, as shown at 30, to form the bottom 65 of the steam jacket and provided with a central opening 31, while resting upon the upper ends of the tubular elements 21 and 25 is a head plate 32, secured in place by bolts 33 and provided with a central opening 34, and the tubular element 26, which constitutes the inner wall of the compression chamber and contains the piston cylinder, is provided at its upper and lower ends with sleeves 35 and 36, which respectively 70 fit in the openings 34 and 31 of the aforesaid head plate 32 and flange 30 and are peripherally flanged, as at 37, to fit within the bore of the cylindrical wall 25 to constitute 75 the bottom of the compression chamber and hold the several parts in their proper relative positions. The lower sleeve 36 also preferably extends downward through an opening 38 in the bed plate 29 of the base 21. The piston is connected by a rod 40 with the 80 crank shaft 41.

Bearing upon and supported by, but preferably spaced from the upper surface of, the head plate 32, is a cap plate 42 also held in place by the bolts 33 and held in the proper 100 position relative to the head plate by means of spacing washers 43. The intermediate space between the head plate and the cap plate constitutes an inlet and exhaust passage 44 for the ingress and escape of atmospheric air. Also carried by the cap plate, and if preferred made integral therewith, as shown in the drawing, is a frusto-conical cap 45 embraced by a ring 46 in which is formed a relief port 47 controlled by a 105 spring actuated valve 48, which is adapted to be unseated under excessive pressure, as

hereinafter more fully described, and therefore constituting a safety valve, which is normally and yieldingly held seated by the spring 49.

5   Mounted at its upper end in the cap 45 and at its lower end in a seat 50, constituting a portion of the bore of the tubular unit 26, shown in detail in Figs. 8 and 9, is the operating valve 29, which is double tapered 10 in form, being tapered in opposite directions toward its extremities from an intermediate point. The valve is provided with an axial bore 51, constituting a relief port which communicates at its lower end with a chamber 15 52 formed in the upper or exterior surface of the cylinder head 53, and with which communicates the interior of the cylinder by means of the ports 4, and which communicates at its upper end, through a port 55 20 with a channel 56 formed in the cap 45, said channel being at all times in communication with the relief port 47 of the ring 46. If at any time during the operation of the engine the interior pressure exceeds the 25 amount determined by the seating spring of the safety valve, a relief will be afforded through the ports 51, 55, channel 56 and relief valve.

30   The compression chamber is of compartmental construction, being divided into any desired number, preferably three compartments, as indicated specifically in Figs. 4, 5 and 6, by radial wings 57, and surrounding the valve between the plane of the cylinder head 53 and the sleeve 35 the compression chamber unit 26 is provided with a series of radial channels 58, as also shown specifically in Figs. 4 and 5, four of such channels being assigned to and used in connection with each compartment of the compression chamber and each of which in succession may be arranged in communication with the piston cylinder through a longitudinal channel port 59 formed in the operating valve and communicating at its lower end with the chamber 52, which as hereinbefore explained is in permanent communication with the piston cylinder through the ports 54. Connecting two of the radial 40 channels 58, in each group of four, with the corresponding compartment of the compression chamber are the ports 60 and 61, hereinafter referred to specifically as expansion and compression ports. Obviously when the 50 channel port 59 of the operating valve is in registration with the radial channels 58 with which communicate the expansion and compression ports, respectively, the corresponding compartment of the compression chamber will be in direct communication with the piston cylinder.

55   The other two radial channels 58, in each group allotted to a compartment of the compression chamber, are provided with 60 ports 62 and 63, hereinafter referred to

specifically as intake and exhaust ports, which are respectively in communication with corresponding ports, similarly designated in the head plate 32, and hence in communication with the inlet and exhaust 70 passage 44 formed by the space between said head plate and the cap plate 42. Therefore, assuming that the operating valve turns continuously in one direction, it will establish communication successively between the radial channels 58 and the piston cylinder and consequently, as to each compartment of the compression chamber, will establish communication between the compression port and the piston cylinder, the 75 intake port and the piston cylinder, the exhaust port and the piston cylinder, and the expansion port and the piston cylinder, successively. Or assuming that the rotative movement of the operating valve is in the 80 opposite direction, the relative arrangement of the parts is such that the piston cylinder will be successively in communication, as to each compartment of the compression chamber with an expansion port, an 85 exhaust port, an intake port, and a compression port, and assuming that the piston is, as shown in Fig. 3, at the upper or outer limit of its stroke, the expansion port will be in communication with the cylinder, and 90 when the piston reaches the inner limit of its stroke the exhaust port will be in communication with the cylinder and will remain exposed until the piston returns to the limit of its outward movement, whereupon the intake port will be put into communication with the piston cylinder, during the inward stroke of the piston, and again the compression port will be opened by the valve during the subsequent outward 95 stroke of the piston, so as to recharge under compression the compartment which was in communication with the piston cylinder during the first of the indicated group of four strokes or cycles of the piston. Obviously, this operation will be repeated as to each of the several compartments of the compression chamber, and if the steam jacket is suitably charged and at a proper 100 temperature, it will be equally obvious that the compressed charge of air, which has been forced thereinto during the final upward stroke or cycle of the piston, will be raised in temperature from that of the surrounding atmospheric air, imported through the intakes, to that which it will derive from the steam, so that when again the expansion port of the same compartment of the compression chamber is placed in communication with the piston cylinder, the piston will 105 receive the effect of the expansion of said charge due to the increase in temperature, supplemented, of course, by the re-action resulting from the previous compression.

110   Preferably the operating valve receives 115

a step by step movement to establish successively communication between the several described ports and the piston cylinder as by employing a counter shaft 64, geared, 5 as at 65, to the crank shaft, which should be provided with a fly wheel 66, and a reciprocatory motion converting element 67 actuated by a cam 68 operating between pins 69 on said slide and provided with pawls 10 70, engaging a ratchet wheel 71, keyed, or otherwise suitably secured to the spindle 72 of said valve. The pawls may be provided with actuating springs 73 to maintain them in proper relation with the ratchet wheel, 15 as shown clearly in Figs. 2 and 11. The slide is slotted, as at 74 and 75, to permit of the reciprocatory motion above indicated with reference to the valve stem and the counter shaft 64.

20 As will be seen by reference to Fig. 7, the cap 45 is provided with a number of lateral ports 55, corresponding with the number of compartments in the compression chamber for permanent communication with the 25 channel 56 and periodic communication with the chamber 52 in the cylinder head through the relief port 51.

From the foregoing description it will be obvious that the engine is of the four cycle 30 type, in that on successive strokes it induces air at atmospheric pressure and temperature through the inlet port which is then in connection by the valve channel port with the piston cylinder and on the return 35 or outward stroke this charge is forced into the compression chamber or into that compartment of said chamber which is then by a forward step movement of the valve brought into communication through a compression 40 port with the piston cylinder, and then said cylinder is brought into communication by a further forward movement of the operating valve with the next compartment of the compression chamber through an expansion 45 port of the latter and an inward impulse is imparted by the charge in said compartment to the piston, and upon the succeeding outward stroke of the piston the expansion charge which has then performed 50 its function is discharged through an exhaust port which is arranged in communication with the cylinder by a further forward movement of the valve, to be succeeded in turn by an inward stroke of the piston 55 and an induction of a new charge of air at atmospheric pressure and temperature. In due course the cylinder is again brought into communication with the first-named compartment of the compression chamber and 60 the piston receives the impulse due to the expansion under a high temperature of the charge which has been compressed into said first-named compartment while at a low temperature, each charge compressed into 65 a compartment of the chamber being ex-

posed to the influence of the heating element for a sufficient length of time to raise its temperature and hence its expansive energy to the degree required to give an effective operating impulse to the piston.

70

Having described the invention, I claim:

1. An expansion engine having a heating element, a compression chamber provided with compression and exhaust ports, said heating element consisting of a steam jacket 75 surrounding the compression chamber, a cylinder, inlet and exhaust ports, and means for successively establishing communication between said ports and the cylinder.

2. An expansion engine having a heating 80 element, a compression chamber provided with communicating compression and expansion ports, a cylinder, inlet and exhaust ports for communication with said cylinder, the compression chamber being of compartmental construction and the said ports being arranged in groups of four for each compartment, a valve seat having independent channels in communication respectively with said ports, and an operating valve 90 mounted in said seat and having a port in communication with the cylinder and adapted for successive communication with said channels to consecutively establish communication between said ports and the cylinder. 95

3. An expansion engine having a heating element, a compartmental compression chamber surrounded by the heating element and inclosing a piston cylinder, the separating wall between said cylinder and the 100 compression chamber being provided with a valve seat in communication with the interior of the cylinder, and lateral channels in communication by compression and expansion ports with the compression chamber, inlet and exhaust ports in communication respectively with other channels connected with said seat, and a valve mounted in the seat and provided with a port for 105 successively establishing communication between said channels and the piston cylinder. 110

4. An expansion engine having concentrically arranged a piston cylinder, a compression chamber, and a steam jacket, the separating wall between the piston cylinder and the compression chamber being extended axially beyond the cylinder head to provide an operating valve seat and laterally communicating independent radial channels, a group of ports respectively in communication with said channels, two of the ports being in communication with a source of fluid at a low temperature and two of said ports being in communication with said compression chamber, and an operating valve 115 mounted in said seat and provided with a port for successively establishing communication between said channels and the piston cylinder. 120

5. An expansion engine having exterior 130

- and interior concentric walls forming an intervening steam jacket, a piston cylinder concentrically arranged within the said interior wall and spaced therefrom to form a compression chamber, a valve seat in communication with the piston cylinder and channels in communication with and radiating from said seat, inlet, exhaust, compression and expansion ports respectively in communication with said radiating channels, the inlet and exhaust ports being in communication with a source of expansive fluid at low temperature and the compression and expansion ports being in communication with the compression chamber, and a valve mounted in said seat and having a port for successively establishing communication between said radiating channels and the piston cylinder.
6. An expansion engine having a cylindrical compression chamber divided by radial webs to form separate compartments and inclosing a piston cylinder of which the wall is extended beyond the cylinder head to form a valve seat and communicating radial channels arranged in groups of four for each compartment of the compression chamber, a heating element having a jacket inclosing said compression chamber, inlet, exhaust, compression and expansion ports respectively in communication with said radial channels, the inlet and exhaust ports being in communication with a source of expansive fluid at a low temperature and the compression and expansion ports being in communication in pairs with the compartments of the compression chamber, and an operating valve mounted in said seat and provided with a port for establishing communication successively between said radial channels and the piston cylinder.
7. An expansion engine having a piston cylinder, a compartmental compression chamber concentrically disposed with reference to said cylinder, an operating valve seat in communication with the cylinder, channels radiating from and in communication with the seat, a heating element surrounding the compression chamber and having a wall disposed concentrically with the exterior wall of the compression chamber, a head plate and a cap plate spaced apart to form an intervening inlet and exhaust passage for atmospheric air, the cap plate carrying a cap interiorly constructed to form a valve seat which is complementary

to the said valve seat, inlet and exhaust ports connecting certain of said radial channels with the said inlet and exhaust passage between the head plate and cap plate, compression and expansion ports connecting the compression chamber with other of said radiating channels, a pressure regulating relief valve, and an operating valve mounted in said complementary seats, having a port for successively establishing communication between said radial channels and the piston cylinder and also having a relief port for establishing communication between the piston cylinder and said relief valve.

8. An expansion engine having a heating element, a compression chamber of compartmental construction exposed to the heating element and provided in communication with each of its compartments with compression and exhaust ports, a cylinder and piston, an operating valve seat in communication with said cylinder, inlet and exhaust ports, channels communicating with the valve seat and respectively in communication with said inlet, exhaust, compression and expansion ports, an operating valve having a port for establishing communication between the said cylinder and either of said channels, and means actuated by the piston for imparting a step by step movement to the valve to successively establish communication between said several ports and the cylinder.

9. An expansion engine having a heating element, a compartmental compression chamber exposed to the heating element, each compartment having compression and expansion ports, inlet and exhaust ports for independent communication with the cylinder, and an operating valve having its seat in communication with the cylinder and all of said ports and having a port for successively establishing communication between said ports and the cylinder, means controlled by the piston being provided for imparting a step by step movement to the valve, to consecutively establish said communications with the several ports with reference to each compartment of the compression chamber.

In testimony whereof I affix my signature in presence of two witnesses.

AUGUST VICTOR LARSON.
